CLAIM

The ornamental design for a rifle barrel adjuster, as shown and described.

DESCRIPTION

FIG. 1 is a perspective view of a rifle barrel adjuster showing my new design, taken from the front, top and right side; FIG. 2 is a perspective view thereof, taken from the rear, top and right side;

FIG. 3 is a front elevational view thereof, the rear elevational view being a mirror image of the front elevational view;

FIG. 4 is a right side elevational view thereof, the left side elevational view being a mirror image of the right side elevational view;

FIG. 5 is a top plan view thereof; and,

FIG. 6 is an exploded perspective view thereof, taken from the front, top and right side.

The various tones of gray shading on the surface portions indicate shaded areas and not surface decoration.
